(57) **CLAIM**

The ornamental design for a “gaming machine,” as shown and described.

DESCRIPTION

FIG. 1 is a perspective view taken from the front and right showing our new design;

FIG. 2 is a front view thereof; and,

FIG. 3 is a right side elevational view thereof, the left side elevational view being a mirror image thereof.

The broken lines showing a portion of a gaming machine is for illustrative purposes only and forms no part of the claimed design.

1 Claim, 3 Drawing Sheets

FIG. 2

FIG. 3
